DRAFT RIGGING.

APPLICATION FILED OCT. 19, 1903.

NO MODEL.

UNITED STATES PATENT OFFICE.

RICHARD D. GALLAGHER, JR., OF NEW YORK, N. Y., ASSIGNOR TO
STANDARD COUPLER COMPANY, OF NEW YORK, N. Y., A COR-
PORATION OF NEW JERSEY.

DRAFT-RIGGING.

SPECIFICATION forming part of Letters Patent No. 752,337, dated February 16, 1904.

Application filed October 19, 1903. Serial No. 177,630. (No model.)

To all whom it may concern:

Be it known that I, RICHARD D. GALLAGHER, Jr., of New York, in the county and State of New York, have invented certain new and useful Improvements in Draft-Rigging; and I do hereby declare the following to be a full, clear, and exact description of the same, reference being had to the accompanying drawings, forming a part of this specification, and to the letters of reference marked thereon.

This invention relates to improvements in apparatus for augmenting the yielding resistance and reducing the recoil of springs by means of friction elements movable upon each other in unison with the spring compression or expansion, the invention being particularly, though not exclusively, adapted for use in railway-car construction and especially in the draft and buffering mechanism thereof.

The invention consists in an apparatus embodying two units, each composed of a yielding member or spring, friction elements, and a casing, the two units being movable toward and from each other, the friction elements being at the proximate ends of the units and adapted to act simultaneously in resisting strains.

The invention further consists in certain novel details of construction and combinations and arrangements of parts, all as will be now described, and pointed out particularly in the appended claims.

Referring to the accompanying drawings, Figure 1 is a half-section and half-plan view of a draft and buffering rigging for railway-cars embodying the present improvements, the end of the draw-bar and sections of the draft-timbers only being shown. Fig. 2 is a horizontal section showing a slightly-modified arrangement of the parts, the draft-timbers illustrated in this instance being of metal.

As before stated, the apparatus of the present invention is composed of two units, and, referring to the form of apparatus shown in Fig. 1, each unit consists of a spring A, mounted in a casing B, with friction elements at one end of the spring and casing.

In the preferred construction the casing B is closed at the outer end and at the inner or open end is provided with inclined walls or surfaces B', with which wedge-blocks C co-operate, said wedge-blocks also co-operating with a central wedge or wedge-shaped follower D, which rests against the spring. The two units are assembled with the friction elements toward each other and are limited in their movements away from each other by suitable stops and shoulders on the draft-timbers. Thus, as shown, each casing is provided with shoulders B'', adapted to seat against stops E, held by the draft-timbers F.

Obviously the positions of the stops and co-operating parts on the movable units may be varied within quite wide limits; but in the preferred construction and as illustrated in Fig. 1 the stops are located in positions corresponding to the positions of the stops now in common use in draft-rigging recommended by the Master Car Builders' Association, and the shoulders on the casings are located near the open ends, so as to fit between such stops, thus adapting the appliances of the present invention for use with the Master Car-Builders' stops and supporting mechanism. In this preferred construction there is also preferably interposed between the proximate friction elements of the two units a friction plate or traveler G, which may have inclined friction-faces, as illustrated, and over which faces the friction-blocks C travel as the two units are forced toward each other by pressure in one direction or the other.

It will be observed that the angles of the inclined friction faces or surfaces may be varied within quite wide limits and dependent upon the frictional resistance it is desired to create for supplementing the spring resistance; but care should be taken that the inclines be such that the parts will readily free themselves and return to normal position, the friction during the return movements being only sufficient to check injurious recoil of the springs.

In operation the two units are usually in-

closed by a strap H, attached at one end to the draw-bar I, which latter may at its rear end abut against one of the units in position to transmit buffing strains thereto, and with such construction strains in one direction or the other will move one of the casings, together with its contained spring, inwardly or toward the other unit, thereby forcing the wedge-blocks C of both ends to travel toward the longitudinal axis of the structure, such movement operating through the central wedges D to compress the springs from their inner or proximate ends. The action is the same in both directions, all of the friction-surfaces of the several elements being put in action in resisting both draft and buffing strains as well as in preventing injurious recoil of the springs.

In Fig. 2 there is illustrated a somewhat simpler form of apparatus embodying the present improvements, and in this instance while the friction elements are of essentially the same construction previously described the wedge-blocks C C of the opposite units are permitted to contact directly with each other and might well be formed integrally of diamond shape, inasmuch as they move in unison. In other words, the traveler G of Fig. 1, together with its friction-faces, is omitted, and the friction is created between the casing and wedge-blocks and between the wedge-blocks and central followers having the inclined faces or wedge-shaped surfaces. In this Fig. 2 also it will be observed that the casings lettered K in this instance are not closed at their rear ends, but are made in the form of castings open at both ends, and separate follower-plates L are located at the outer ends of the casings to form the abutments against which the springs will rest and to which the draft and buffing strains will be directly applied, said follower-plates, however, serving to advance one or the other of the casings in accordance with the direction of movement, the operation, except as above indicated, being in all respects similar to the operation of the apparatus illustrated in Fig. 1.

When follower-plates are employed, as in Fig. 2, they preferably also constitute the shoulders which coöperate with the stops M on the draft-timbers to limit the outward movement of the units, said stops in this instance being located a sufficient distance apart to permit of the insertion of the entire apparatus between them. With this construction ordinary Master Car-Builders' springs may be employed, and while the range of spring movement is equivalent to a range of movement double that of a single spring the range of draw-bar movement is equal to that of a single spring only, because of the differential movement between the spring-casings and proximate followers which compress the springs from their inner ends.

Having thus described my invention and in

what manner the same is to be performed, what I claim as new, and desire to secure by Letters Patent, is—

1. In a rigging such as described, the combination of two units all of the members of which are movable longitudinally of the line of strain, each of said units embodying resilient members and friction elements at one end of said resilient members, said units being assembled in alignment in the line of strain with their friction elements in proximity; substantially as described.

2. In a rigging such as described, the combination with oppositely-disposed springs arranged in the line of strain to be resisted and friction elements interposed between the proximate ends of said spring, of casings movable toward and from each other and having friction-surfaces for rendering the friction elements operative during the relative movement of the casings; substantially as described.

3. In a rigging such as described, the combination of two units movable toward and from each other and each embodying the following instrumentalities, to wit; a casing, a spring arranged longitudinally of said casing, a follower having inclined faces and supported by said spring and wedge-blocks interposed between said follower and casing so as to be moved transversely of the line of strain by the relative movement of the casing and follower, the said units being assembled with their inclined-faced followers and wedge-blocks in proximity; substantially as described.

4. In a rigging such as described, the combination of the following instrumentalities, to wit; wedge-blocks movable transversely of the line of strain, oppositely-disposed followers interposed between said wedge-blocks, oppositely-disposed casings inclosing said wedge-blocks and movable toward and from each other in the line of strain, and oppositely-disposed springs arranged outside of the followers in the line of strain, with means for moving said casings in the line of strain to effect the transverse movement of the wedge-blocks and longitudinal compression of the springs from their proximate ends; substantially as described.

5. In a rigging such as described, the combination with the oppositely-arranged casings closed at their outer ends and open at their proximate ends, springs in said casings, followers interposed between the proximate ends of said springs and friction elements interposed between said followers and the proximate faces of the casings; substantially as described.

6. In a rigging such as described, the combination with the oppositely-disposed casings movable toward and from each other and closed at their outer and open at their inner ends, springs mounted in said casings, wedge-shaped followers interposed between proximate ends

of the springs and wedge-shaped friction elements interposed between the proximate ends of the casings and followers whereby said friction elements are made active by an inward movement of either casing; substantially as described.

5. In a rigging such as described, the combination with oppositely-disposed casings having their proximate ends open, springs mounted in said casings and friction elements interposed between the proximate ends of the springs and confined by the casings, of stops for limiting the movement of said casings away from each other but permitting of a relative movement of the casings toward each other; substantially as described.

7. In a rigging such as described, the combination with the oppositely-disposed casings movable toward and from each other and having their proximate ends open, springs mounted in said casings, followers interposed between the proximate ends of said springs, friction elements between the followers and casings respectively and a traveler interposed 25 between the friction elements of the respective casings; substantially as described.

9. In a rigging such as described, the combination with the oppositely-disposed casings movable toward and from each other and having their proximate ends open, springs mounted 30 in said casings, wedge-shaped followers interposed between the proximate ends of said springs, wedge-shaped friction elements interposed between the followers and casings respectively, and a traveler interposed between 35 the friction elements of the respective casings; substantially as described.

10. In a draft-rigging and buffing-rigging, the combination with stops, of oppositely-disposed casings having their proximate ends 40 open and their distant ends extending in line of strain beyond the stops, shoulders on the proximate ends of said casings cooperating with the stops to limit the movement of the casings away from each other, the springs 45 mounted in the casings and friction elements interposed between the proximate ends of the springs and casing; substantially as described.
